UNITED STATES PATENT OFFICE.

JOHN T. HICKS, OF BOSTON, MASSACHUSETTS, ASSIGNOR TO THE HOTEL SECURITY CHECKING COMPANY, OF PORTLAND, MAINE; BOSTON, MASSACHUSETTS, AND NEW YORK, N. Y., A CORPORATION OF MAINE.

SLIDING-DOOR FASTENER.

SPECIFICATION forming part of Letters Patent No. 686,732, dated November 19, 1901.

Application filed February 21, 1901. Serial No. 48,239. (No model.)

To all whom it may concern:

Be it known that I, JOHN T. HICKS, a citizen of the United States of America, and a resident of the city of Boston, county of Suffolk, 5 and State of Massachusetts, have invented certain new and useful Improvements in Fasteners for Sliding Doors, of which the following is a specification.

This invention relates to a fastener for sliding doors of the kind used on show or exhibition cases and similar constructions, the object being to provide a simple, cheap, and efficient locking device which cannot easily get out of order and which will be durable, as 15 well as of unusual strength; and the invention therefore consists, essentially, in the construction, arrangement, and combination of parts and in numerous details and peculiarities thereof, substantially as will be hereinafter more fully described and claimed.

In the accompanying drawings, illustrating my invention, Figure 1 is a perspective view of a show-case provided with my improved fastener. Fig. 2 is a cross-section of the 25 same. Fig. 3 is a detail perspective view of the locking-bar. Fig. 4 is a detail view showing a modified form of the device that engages the locking-bar. Fig. 5 is a sectional view of this modification.

Similar numerals of reference designate corresponding parts throughout all the different figures of the drawings.

1 denotes a show-case as shown in the drawings. It is of a common form, having 35 a wooden frame and glass sides and top; but this form is given simply by way of example, and I reserve the liberty of applying my fastener to any style of show-case to which it may be found applicable. The show-case 1 has at the rear side three sliding doors 2, 3, and 4, which move in suitable ways or grooves, the doors 2 and 4 being set slightly to the rear of the middle door 3, so that when said doors 2 and 4 are moved for the purpose 45 of permitting access to the interior of the show-case they will slide over the face of the middle door 3, and when said middle door 3 is moved it will slide behind one or the other of the doors 2 or 4, it being noted, of course, 50 that each of the three doors is slidable and

permits access to the portion of the show-case immediately in front of it. The common practice in securing these doors against unauthorized entry into the show-case is to provide each one of them with some sort of a locking device that will cause an engagement between the frame of the show-case and the door; but so far as I am aware such devices are intricate in construction, as well as expensive, and have proven failures in use. 60 I aim by the employment of a device of extreme simplicity to effectively fasten all three doors with a single fastening device.

The middle door, as 3, is provided at a point near the bottom edge thereof with a projecting horizontal bolt or pin 5, which may be fastened to the door 3 in any desired manner. It may be integral with a small plate 6, which is secured to door 3 by means of screws or pins 7. 8 designates a locking-bar of metal, wood, or other strong material and of a suitable length to fit neatly between the adjacent edges of the doors 2 and 4 when the latter are in the closed position. (Shown in Fig. 1.) Bar 8 has a central orifice or slot 9 of proper size and shape to enable the bolt 5 to pass through it when the bar is placed in its operative position. (Shown in Fig. 1.) The bolt 5 is provided near its outer end with an eye or hole 10, intended to 70 be engaged by a padlock 11 after the bar 8 has been placed in position for the purpose of preventing the removal of the bar. As before suggested, the bolt 5 is situated near the lower edge of the door 3, to which it is attached, in order that when the locking-bar is 75 in position its bottom edge will rest quite or nearly in contact with the adjoining edge of the frame of the show-case, so that said locking-bar will be kept in its horizontal position 80 and cannot be shifted to an extent that would destroy its function of serving as a barrier between the doors 2 and 4. After bar 8 has been placed upon the bolt 5 the padlock 11 85 may be fixed in place. The removal of the padlock of course permits bar 8 to be removed and the show-case unlocked. When bar 8 is in the position shown in Fig. 1, it will 90 be observed that door 2 cannot be moved to the right, door 4 cannot be moved to the left, 95 and

and door 3 is also stationary and immovable because of the relations that these parts bear to the locking-bar and the pin 5.

A modification of the bolt device carried by 5 the middle door is shown in Fig. 4, wherein the middle door 3 is provided near its lower edge with a square recess 12, in which is sunk one leaf 13 of a two-leaf hinge, said leaf 13 being fastened in place by means of screws 10 14. The other leaf 15 of this hinge device is adapted to open downward away from the stationary leaf 13; but it will be noted that the recess 12 is deep enough to contain both leaves when leaf 15 is closed against leaf 13, 15 thus keeping leaf 15 when desired flush with or below the surface of door 3, so that there may be no projecting points on the face of said door. Hinge-leaf 15 is provided near its end with a slot or orifice 16. The locking- 20 bar 8 has a slot 17 therein of somewhat different form from the slot 9 shown in Figs. 1 and 3, but having a similar function, in that it is designed to receive the movable leaf 15. With this modification, therefore, it will be 25 understood that when the bar 8 is to be placed in position between doors 2 and 4 the leaf 15 will be removed from recess 12 and placed in the horizontal position shown in Fig. 4, after which the locking-bar may be 30 placed over the leaf 15 and then the padlock

11 caused to engage the eye 16. In Fig. 5 the shape of the recess 12 is shown and the position of the hinge devices when both leaves are contained in said recess, and the dotted lines indicate the position of leaf 15 when removed from the slot and placed in its operative position. 35

Having thus described my invention, what I claim as new, and desire to secure by Letters Patent, is—

1. In a fastener for sliding doors, the combination with the case, of a series of sliding doors, a fixed device on the middle door of the series, and a locking-bar engaging said device, together with means for keeping the 45 locking-bar in place.

2. In a fastener for sliding doors, the combination with the case, of a series of sliding doors, the middle one of which is provided with a fixed device consisting of a foldable 50 hinge, one leaf of which is perforated, a locking-bar adapted to engage the perforated leaf, and a padlock for keeping the bar in place.

Signed at New York city this 16th day of November, 1900.

JOHN T. HICKS.
